US0D1096458S

(12) **United States Design Patent** (10) **Patent No.:** **US D1,096,458 S**
(45) **Date of Patent:** **** Oct. 7, 2025**

(54) **BARBECUE THERMOMETER SET**

(71) Applicant: **Shenzhen Hongkang International Electronic Technology Co., Ltd., Shenzhen (CN)**

(72) Inventors: **Qilong Ai, Shenzhen (CN); Jieyuan Tan, Shenzhen (CN)**

(73) Assignee: **Shenzhen Hongkang International Electronic Technology Co., Ltd., Shenzhen (CN)**

(**) Term: **15 Years**

(21) Appl. No.: **29/955,794**

(22) Filed: **Aug. 4, 2024**

(30) **Foreign Application Priority Data**

Jun. 25, 2024 (CN) 202430390744.3

(51) LOC (15) Cl. **10-04**

(52) U.S. Cl. **D10/57**
USPC .....

(57) **CLAIM**

The ornamental design for a barbecue thermometer set, as shown and described.

DESCRIPTION

FIG. 1 is a front perspective view of a barbecue thermometer set, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is the barbecue thermometer in a state.

The broken lines in the drawings illustrate the portions of the barbecue thermometer set, which form no part of the claimed design.

1 Claim, 9 Drawing Sheets
